UNITED STATES PATENT OFFICE

111,799

DESIGN FOR A SCHOOL SYMBOL

Matilda F. Warner and Marian Jean Warner,
Oakland, Calif.

Application September 1, 1936, Serial No. 64,675

Term of patent 14 years

To all whom it may concern:

Be it known that we, Matilda F. Warner and Marian Jean Warner, citizens of the United States, residing in the city of Oakland, county of Alameda, State of California, have invented a new, original, and ornamental Design for a School Symbol, of which the following is a specification, reference being had to the accompanying drawing, forming a part thereof.

Figure 1 is a front view of a school symbol showing our new design.

Figure 2 is a sectional view taken substantially along the line 2—2 of Figure 3 showing how the yarn with which our new design is made radiates

outwardly from the center point of each of the component parts, head, body and legs. Due to this construction only the cut ends of the yarn radiating outwardly from the center are visible thus giving a soft feel and a fluffy appearance as contrasted with the hard appearance of the typical stuffed or wound type of animal.

Figure 3 is a side view of our new design for a school symbol as shown in Figure 1.

We claim:

The ornamental design for a school symbol, as shown and described.

MATILDA F. WARNER.
MARIAN JEAN WARNER.
